(57) **CLAIM**

The ornamental design for a bottle, as shown and described.

DESCRIPTION

FIG. 1 is a first perspective view of a bottle.

FIG. 2 is a second perspective view of the bottle shown in
FIG. 1.

FIG. 3 is a front view of the bottle shown in FIG. 1.

FIG. 4 is a back view of the bottle shown in FIG. 1.

FIG. 5 is a left view of the bottle shown in FIG. 1.

FIG. 6 is a right view of the bottle shown in FIG. 1.

FIG. 7 is a top view of the bottle shown in FIG. 1.

FIG. 8 is a bottom view of a bottle shown in FIG. 1.

FIG. 9 is a first perspective exploded view of the bottle
shown in FIG. 1; and,

FIG. 10 is a second perspective exploded view of the bottle
shown in FIG. 1.

The broken lines formed by equal length dashes (dash-dash
lines) included in the drawings represent unclaimed portions
of the bottle and form no part of the claimed design.

1 Claim, 9 Drawing Sheets

Related U.S. Application Data

a continuation of application No. 29/587,289, filed on Dec. 12, 2016, now Pat. No. Des. 844,435, which is a continuation of application No. 29/587,298, filed on Dec. 12, 2016, now Pat. No. Des. 844,436.
